EAVES THROUH STRAINER

Axel S. Wahl, Jersey City, N. J.

Application February 25, 1936, Serial No. 65,739

3 Claims. (Cl. 210—170)

This invention relates to a strainer for drain pipes for eaves troughs.

The invention has for its object to provide, in a manner as hereinafter set forth, an effective and economical strainer constructed entirely of interengaging lengths of wire and which may be expeditiously inserted in the mouth of the vertical drain pipe of an eaves trough.

A further object of the invention is to provide, in a manner as hereinafter set forth, a strainer for the purpose referred to formed of individual spaced wires looped together intermediate their ends and connected together at their upper ends in spaced relation without the addition of a separate tying or a separate spacing means for the wires.

The invention not only embodies the objects and advantages of the form of strainer disclosed by my application filed April 20, 1935, Serial No. 17,516, but has for its further object to provide a skeleton strainer formed of a series of spaced wires having inherent means intermediate their ends for spacing and connecting them together and interengaging inherent means at their upper ends for directly spacing and connecting them together thereby overcoming the employment of a coupling in the form of an annulus as is employed in the form of strainer disclosed by the application aforesaid.

Further objects of the invention provide, in a manner as hereinafter set forth, a strainer for the purpose referred to which is simple in its construction and arrangement, strong, durable, compact, readily assembled, thoroughly efficient in its use, and inexpensive to manufacture.

With the foregoing objects in view and to others which may hereinafter appear, the invention consists of the novel construction, combination and arrangement of parts as will be more specifically referred to and are as illustrated in the accompanying drawing, wherein is shown an embodiment of the invention, but it is to be understood that changes, variations, and modifications may be resorted to which fall within the scope of the invention as claimed.

In the drawing:

Figure 1 is a side elevation of the strainer,
Figure 2 is a top plan view thereof,

Figure 3 is a fragmentary view in side elevation illustrating the manner of connecting the upper ends of the wires together,

Figure 4 is a fragmentary view in perspective illustrating the form of the intermediate stretch of each of the wires, and

Figure 5 is a top plan view illustrating the form of the upper end of each of the wires.

The strainer is of annular cross section and formed of a series of spaced individual wires 6 arranged in the form of a skeleton body having its upper portion 7 of bulbous contour and its lower portion 8 substantially of uniform diameter.

Each wire 6 includes a lower straight upstanding stretch 9, an intermediate horizontal stretch 10 disposed substantially at right angles to the upper end of stretch 9 in an anti-clockwise direction and an outwardly curved upper stretch 11 terminating at its upper end into laterally directed substantially horizontally disposed curved portions 12 and 13 formed integrally with the upper end of the wire and providing oppositely directed hook members for co-operation with an attachment to adjacent wires.

The intermediate stretch 10 consists of a portion 14 which inclines downwardly relative to the upper end of stretch 9 and merges into the inner side of a U-shaped portion 15 offset with respect to the portion 14.

The stretches 10 maintain the stretches 9 in spaced relation. Each stretch 9 of a wire 6 extends through the U-shaped portion 15 of an intermediate stretch 10 of an adjacent wire 6. The lower end of the stretch 11 of each wire 6 is formed with an incurved portion, as at 16 which merges into the U-shaped portion 15 of said wire 30

The upper end of each stretch 9 is arranged within a U-shaped portion 15 of an intermediate stretch. The portion 14 of each intermediate stretch seats on a side of the portion 15 of an adjacent stretch and opposes the outer side of the incurved lower end 16 of a stretch 11 which merges into that side of the portion 15 upon which a portion 14 seats. The stretches 10 connect the stretches 9 with the stretches 11 and maintain the wires in spaced relation. The manner in which the stretches 10 are formed, their relation to the stretches 9 and 11 and the manner in which the lower ends of the stretches 11 are formed provide for the wires 6 to interengage intermediate their ends and for coupling 45 the wires 6 together.

The hook-parts 13 at the upper ends of the stretches 11 are substantially closed and have the curved portion 12 extend therethrough whereby the upper ends of the wires 6 are connected together and the stretches 11 are maintained in spaced relation.

The stretches 10 offset the stretches 11 relatively to the stretches 9 whereby a stretch 11 of one wire 6 will have its lower end aligning sub- 55

stantially with the upper end of a stretch 9 of an adjacent wire 6. The stretches 11 project outwardly with respect to the upper ends of the stretches 9.

5. The stretches 10 provide spacers for the wires 6. The hook-parts 13 provide couplers for the upper ends of the stretches 11 and due to the arrangement of the curved parts 12 and hook-parts 13, the upper ends of the stretches 11 are disposed in a circular row. The stretches 9 form what may be termed a skeleton flexible extension which may be forced down into the upper end of the drain pipe which is connected to the eaves trough in a manner well known in the art.
10. The manner in which each of the wires is constructed provides for assembling, by hand the wires in cage formation with the wires connected together intermediate their ends and directly secured together at their upper ends.
15. What I claim is:—
1. An eaves-trough strainer comprising a plurality of upwardly extending wires, said wires formed to provide a lower cylindrical portion and

an upper bulb-shaped portion, the upper end of each of said wires terminating in laterally extending curved portions formed integrally with the upper end of the wire and formed to provide oppositely directed hook members for cooperation with and attachment to adjacent wires.

2. An eaves-trough strainer in accordance with claim 1 wherein each of the said wires is formed to provide an intermediate substantially horizontal portion, the ends of said intermediate portion terminating in curved portions, said curved portions adapted for co-operation with and attachment to adjacent wires.

3. An eaves-trough strainer consisting of a plurality of upwardly disposed wires, each of said 15 wires having a substantially vertical lower portion, an inwardly curved upper portion and means formed integrally with the upper end of the wire for co-operation with and attachment to adjacent wires, said means including laterally 20 extending curved portions forming oppositely directed hook members.

AXEL S. WAHL.
